LOAD SUPPORTING PALLET

Russell E. Watts, Dallas, Tex., assignor to Fleming & Sons, Inc., Dallas, Tex., a corporation of Texas

Application April 3, 1950, Serial No. 153,657

9 Claims. (Cl. 248—120)

1

This invention relates to new and useful improvements in load supporting pallets.

The invention is particularly concerned with pallets of inexpensive manufacture adapted for use with lift trucks having lifting forks or prongs.

One object of the invention is to provide an improved pallet of the type described which is sufficiently cheap and economical to manufacture and use as to permit its utilization in only one shipping operation with subsequent destruction, whereby the expense of returning the pallet to the point of shipping is avoided.

A particular object of the invention is to provide an improved pallet of the character described which is formed of cardboard or chipboard or other similar material, and which includes a novel supporting element structure.

A further object of the invention is to provide an improved pallet of the character described having a novel arrangement for the bottom or base plate of said pallet.

A construction designed to carry out the invention will be hereinafter described together with other features of the invention.

The invention will be more readily understood from a reading of the following specification and by reference to the accompanying drawings, wherein examples of the invention are shown, and wherein:

Fig. 1 is a view in perspective, partially broken away, illustrating the structure of a pallet constructed in accordance with this invention,

Fig. 2 is a schematic view in side elevation illustrating the mode of use of the pallet,

Fig. 3 is an enlarged view in perspective of a modified form of one of the supporting elements,

Fig. 4 is a horizontal, cross-sectional view of a further modification of the supporting element,

Fig. 5 is a view similar to Fig. 1 illustrating a modified form of the pallet employing a further modification of the supporting elements,

Fig. 6 is a vertical, cross-sectional view taken upon the line 6—6 of Fig. 5, and

Fig. 7 is an enlarged, horizontal, cross-sectional view of one of the supporting elements shown in Fig. 1.

In the drawings, the numeral 10 designates, in general, a pallet structure having an upper plate 11 and a lower plate 12. The plates 11 and 12 are arranged in spaced, parallel relationship, and preferably are formed of heavy cardboard, chipboard, pasted or laminated chipboard, or the like. A plurality of supporting elements 13 are disposed between the plates 11 and 12, and preferably are arranged symmetrically in longitudinal and transverse rows in spaced relationship. With this arrangement, the forks 14 of a conventional lift truck 15 may be inserted into the spaces between adjacent rows or columns of the supporting elements 13, as illustrated in Fig. 2, whereby the pallet may be lifted

2

upon said forks. Obviously, since the supporting elements 13 are spaced from one another both transversely and longitudinally, the forks of a lift truck may be introduced from either end of the pallet 10, or from either side thereof. Normally, the pallets are made in a substantially rectangular shape, but may be square, considerably elongated, or may have any other suitable or desirable shape or configuration.

10 The supporting elements 13 also are formed from heavy cardboard, or a similar material in order that the cost of the pallet may be kept as low as possible and to permit the discarding of the pallet after one use in a shipping operation. 15 The form of the supporting element illustrated in Fig. 1 includes a hollow, rectangular or square box 16 having its upper and lower ends open and disposed adjacent the facing surfaces of the plates 11 and 12. An open-ended tube or cylinder 17 of arcuate cross-section is disposed within the box 16 and has its upper and lower ends serrated to form a plurality of laterally-directed tabs or fingers 18. These tabs are glued, cemented, or otherwise affixed to the juxtaposed surfaces of the plates 11 and 12 and provide a very secure and substantial bond between said plates and the supporting elements. Within the cylinder 17 is provided a supporting and strengthening web 19 formed of two semi-cylindrical sections having their outer surfaces meeting tangentially and jointed by a staple 20, as shown in Fig. 3. If desired, the web 19 may be secured to the inner surface of the cylinder 17 by gluing or cementing, or the web may be left freely slideable within the cylinder since it is confined therein by the plates 11 and 12. Also, the box 16 may be similarly secured to the outer surface of the cylinder, or may have its upper and lower edges secured to the tabs 18, or both securing procedures may be employed. None of the additional securing is essential to the invention although it has been found preferable to secure the box 16 to the tabs 18 at several points.

45 The structure which has been described, which includes a cylinder embraced by the rectangular box 16 is unique in its structural characteristics in that it provides a structure which is highly resistant to longitudinal loads or columnar stresses. Thus, even though the entire supporting element 13 is formed of cardboard or some similar material, it is of sufficient strength to support average loads and permits the use of the pallet 10 with all but the heaviest materials. The pallet has performed exceedingly well in actual use with large stacks of paper and cardboard and has withstood both the loads applied and the normal abuse received in shipping operations. Nevertheless, the cost of manufacture and use of the pallet is sufficiently low to permit its being discarded after only one use in transportation.

50 A modified form of the invention is shown in

60

Fig. 3 of the drawings in which the tabs 18 are omitted from the cylinder 17, and the box 16 is provided with laterally-directed flanges or tabs 21 which are secured to the facing surfaces of the plates 11 and 12. It has further been found that the web 19 may be omitted in certain instances without reducing the strength of the pallet below that necessary to handle certain types of merchandise. This further modification of the supporting element is illustrated in Fig. 4 wherein it is also brought out that the cylinder 17 may be formed with a lapped construction, as well as with the tube construction shown in Figs. 1 and 3. In the form of the cylinder shown in Fig. 4, a sheet of cardboard is merely bent into a cylinder, and the lapping ends are stapled together, as shown at 22, to form a completed cylinder. There is no appreciable loss of strength in this structure, and the cost of manufacture of the pallet is reduced somewhat thereby.

The lapped construction of the inner cylinder 17 may be applied to the form of the invention shown in Fig. 1 with the simultaneous use of the web 19, as illustrated in Fig. 7, or with the omission of the internal web, as shown in Fig. 5.

A modification of the base plate 12 is also permissible, and in some cases desirable for ease in handling the pallet when a load is secured thereto. In this modification, the base plate 12 is replaced by a plurality of somewhat smaller base plates 23, each extending transversely of the pallet and being secured to the lower ends of one transverse row of the supporting elements 13, as shown in Fig. 5. With this structure, economy is effected both in the quantity of material required for the base plate and in the smaller area of the pieces of board required to form the lower portion of the pallet. It is possible to employ somewhat smaller pieces of board for the base structure and hence to make use of portions of board which otherwise would be scrap since they would not be of sufficient size to form one of the base plates 12.

The invention which has been described herein, and the modification thereof, employ the most inexpensive forms of paper or fiber board and achieve a structure of adequate strength for normal commercial use without requiring intricate shapes or expensive and complex forms of paper or fiber board. It is further to be noted that each element of the pallet structure may be pressed or folded into a flat form whereby the various elements of the pallet may be shipped in a knocked-down or disassembled form and will occupy a minimum of space. Thus, the raw materials or elements of the pallet may be shipped from one point to another at low cost, and may be assembled for use at the point of destination. The assembly of the pallets is simple and may be carried out by unskilled labor through simple stapling and gluing or cementing operations, and meanwhile, quantities of the knocked-down pallets may be stored in a minimum of space. The structure of the pallet, therefore, not only permits the employment of low-cost materials, but permits the storage and shipping of quantities of the pallets in a minimum of space and with a minimum of expense.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A pallet having upper and lower plates and supporting elements secured between the plates, said supporting elements including an inner cylinder having its axis extending perpendicularly to the plates, and an open-ended outer box embracing the annular periphery of the cylinder whereby all side walls of the box and the cylinder wall cooperate to support the upper plate, the supporting elements having laterally directed tabs hingedly connected thereto and secured to the upper and lower plates.
- 15 2. A pallet having upper and lower plates with facing sides and supporting elements secured between the plates, said supporting elements including, an inner cylinder member, and an outer rectangular box member embracing said cylinder member, one of said members having laterally-directed tabs secured to the facing sides of the plates.
- 20 3. A pallet having upper and lower plates and supporting elements secured between the plates, said supporting elements including, an inner cylinder member, and an outer box member embracing said cylinder member, one of said members having outwardly and laterally directed tabs secured to the plates, said tabs extending from all sides of the latter member.
- 25 30 4. A pallet having upper and lower plates and supporting elements secured between the plates, said supporting elements including, an inner cylinder, and an open-ended outer box embracing said cylinder, said cylinder having laterally directed tabs secured to the plates, said tabs extending from all sides of the cylinder and projecting between the ends of the box and the plates.
- 35 40 5. A pallet having upper and lower plates and supporting elements secured between the plates, said supporting elements including, an inner cylinder, and an outer box embracing said cylinder, said box having laterally directed tabs secured to the plates, said tabs extending from all sides of the box.
- 45 6. A pallet having upper and lower plates and supporting elements secured between the plates, said supporting elements including, an inner cylinder having its axis extending perpendicularly to the plates, an open-ended outer box embracing the annular periphery of the cylinder whereby all side walls of the box and the cylinder wall cooperate to support the upper plate, and a web embraced by said cylinder.
- 50 55 7. A pallet as set forth in claim 6, wherein the web includes a pair of semicylindrical members having their outer faces engaging tangentially.
- 60 8. A pallet as set forth in claim 6, wherein the cylinder, the box and the web are substantially co-extensive.
- 65 9. A pallet as set forth in claim 1, wherein the cylinder is formed of a rectangular sheet formed into cylindrical shape with its ends overlapping and secured together.
